UNITED STATES PATENT OFFICE

GUSTAV F. C. BAUER, OF TONAWANDA, NEW YORK, ASSIGNOR TO NATIONAL POLICE SIGNAL COMPANY, OF BUFFALO, NEW YORK, A CORPORATION OF NEW YORK

POLICE-SIGNAL SYSTEM

Application filed July 13, 1928. Serial No. 292,360.

This invention relates to an electrical signalling and communicating system and more particularly to a system of this character for use between a central station and a plurality 5 of substations for police purposes.

The system embodying this invention is a simplification and improvement of the systems described in Patents No. 1,080,018, Louis W. Miller, December 2, 1913; 1,218,682, Louis 10 W. Miller, March 13, 1917; and more particularly Patent No. 1,552,843, William W. Kidney and Gustav F. C. Bauer, Sept. 8, 1925.

In its general organization this invention 15 includes a plurality of telephone circuits between a central station switchboard and a plurality of police boxes or substations so that a telephone conversation can be carried on between the same, means for giving a wagon call signal and a recorded report from the substation to the central station, and means for giving either an audible or a visual signal from the central station at the substation or substations, so as to call a nearby 20 officer to the substation or police box for the purpose of giving him instructions.

Police signal systems such as the system embodied in the present invention, are basically telephone systems, but there is a distinct difference between a signal system of the 25 present type and an ordinary telephone system. In the conventional manual telephone system, the practice is to incorporate the ringing circuits for calling substations in the cord circuits. This is essential in conventional 30 telephone circuits because the switchboard is employed merely to interconnect substations that wish to communicate with each other.

In a police signal circuit of the present 40 order, the most important service is of a different character, that is, in most cases the telephone conversation is carried on between the operator at the switchboard and the substations and the officers on duty are called to the substations by means of signals provided at the substations. The officer's beat generally includes a number of police boxes or substations so that the officer can be called 45 from the central station while on any part of his beat, or he can conveniently call the cen-

tral station to register a report, call a wagon or for any other purpose. For convenience and simplicity of operation it is therefore essential that means be provided for direct signalling on all substation circuits, particularly in view of the fact that in many service calls, it is necessary to obtain an immediate 55 telephone conversation with all of the officers available in the precinct. Special provisions are therefore made in each substation circuit 60 for operating substation signals without having to resort to the conventional telephone circuit which in this class of service would be exceedingly slow and cumbersome.

The present signal system is, however, also 65 arranged so as to be used as a conventional telephone system for interconnecting substations by means of cord circuits, trunk lines, etc. (not shown).

It is also desirable in police signal work 70 to provide two distinct types of substation signals, first, a visual signal which is mounted so as to be visible at a distance from the substation and is used where immediate communication is not essential, and second, an 75 audible signal for use in emergencies where immediate response is necessary.

As the visual signal is not of a disturbing 80 nature in the vicinity of the substation, it can be operated for more or less extended time periods without causing annoyance to the public. The audible signal, on the other hand, must have a distinctive sound of such volume as to be audible over an area and therefore provision must be made to prevent 85 such audible signals from being left in operation for any period of time that might cause annoyance.

As heretofore constructed, the signals at 90 each substation or box were controlled by a double throw signal switch, which when thrown one way would place the visual signal in circuit with a flasher and when thrown the other way would place the audible signal 95 in circuit with the flasher. By this system if five or more boxes on the beat of an officer, or on the beats of several officers were being signalled, all of the signal keys would have to be set to give a visual signal, all would have 100

to be thrown the other way for a short time to give an audible signal and all would have to be again thrown back to give a continued visual signal. The individual manipulation of this number of keys to give the desired signals necessarily took time, and particularly if several officers were being called, some of whom responded more promptly than others, created a great deal of confusion in manipulating the signal keys and other devices of the switchboard.

The present invention proposes a police signal system in which the substation signal keys have only one operative position, i. e., each signal key can be moved from its inoperative position to one operative position in which operative position the corresponding substation circuit is set up for substation signal operation. By these keys as many station circuits may be set up for signal operation as may be necessary, but the signal keys are nonselective as to the type of substation signal actuated. In the normal condition of the substation circuits, the source of energy for signal operation is arranged to supply energy for visual signal operation. It therefore follows that in the normal condition of the substation circuits, the setting of the signal keys will effect an operation of the visual signals of the corresponding substations.

For the purpose of actuating the audible substation signals a master signal switch is included in the signal energy supply circuit, this master signal switch being common to all of the substation circuits and being so arranged that the substation signal circuits set up by the operation of the individual signal keys are changed so as to supply energy to the audible signal only.

By this means, the proper signal keys are set to signal the desired boxes or substations and a normal visual signal is effected, and to then effect an audible signal at each of these boxes, the switchboard operator presses the master signal switch which cuts off the visual signals and places the audible signals in circuit with the set keys. After a few blasts on the audible signal, the master signal switch is released and the visual signals automatically continued until the officer responds to the call and the signal keys are thrown back to their inoperative position.

The provision of this master signal switch therefore provides a very simple and direct method of changing from visual signals to audible signals on any group or combination of substation circuits that may be placed in operation at any time, and a saving in time and confusion is effected in manipulating the substation signals.

A further object is to provide such a circuit which contains all of the essential elements of a police signal system, which is

simple in arrangement, convenient in use, and is readily installed and repaired.

In the accompanying drawings:

Figure 1 is a diagrammatic representation of that portion of the police signal circuit which is arranged at the central station. Figure 2 is a diagrammatic representation of that portion of the police signal circuit which is arranged at the substation or police box.

The telephone circuit

The central station circuit shown in Fig. 1 and the police box or substation circuits shown in Fig. 2 are connected by the usual telephone lines each comprising a tip side 5 and a ring side 6. At the police box the usual telephone receiver 7, hook switch 8 and transmitter 9 are in circuit with the tip and ring sides of the line circuit, these elements being arranged in the usual manner so that when the receiver 7 is removed from the hook switch 8, an electrical circuit is established through the tip side of the circuit, receiver, transmitter and ring side of the line circuit.

At the central station the tip side 5 of the line circuit is connected to one armature 10 of a line relay 11, this armature normally or in the deenergized condition of the line relay 11 being held in contact with a wire 12 which connects with the tip spring contact 13 of the line jack 14. This line jack wire 12 is also connected by a wire 15 with a line relay 16, the other terminal of this line relay 16 being connected with a wire 17 the other end of which connects by a wire 18 with a battery B and a ground G.

The ring side 6 of the line is connected with the other armature 19 of the line relay 11, this armature normally or in the deenergized condition of the relay 11 being held in contact with a wire 20 which connects with the ring spring contact 21 of the line jack 14. This line jack wire 20 also is connected by a wire 22 with the movable wagon call release contact 23 of the signal key 24. This movable wagon call release contact 23 normally contacts with a fixed wagon call release contact 25 which is connected by a wire 26 with a line relay 27. The other terminal of this line relay 27 is connected by a wire 28 with a wire 29, this wire 29 being connected by a wire 30 with the battery B.

One of the armatures 31 of the relay 16 is connected by a wire 32 with the battery wires 29 and 30 and upon energization of this relay 16, this armature 31 is moved into contact with a wire 33. This wire 33 is connected with one of the fixed contacts 34 of the line jack, this fixed contact normally, or in the unplugged condition of the jack, engaging the spring contact 35 thereof. This spring contact 35 is connected by a wire 36 with a white line lamp 37, the other terminal of which is grounded. This white line lamp 37 is closely

associated with the line jack 14 on the switchboard.

When a policeman at the police box or substation wishes to talk with the switchboard operator, he lifts the receiver 7 at the box. This establishes a circuit through battery B, wires 30, 29 and 28, line relay 27, wire 26, fixed wagon call release contact 25, movable wagon call release contact 23, wires 22 and 20, armature 19 of the line relay 11, ring side 6 of line circuit, transmitter 9, receiver 7, hook switch 8, tip side 5 of circuit, armature 10, wires 12 and 15, line relay 16, wires 17 and 18 to the grounded side of the battery B.

Upon the energization of the line relay 16, its armature 31 is pulled up and a circuit is established through battery B, wires 30, 29 and 32, armature 31 of relay 16, wire 33, fixed contact 34 of the line jack, spring contact 35, wire 36, white line lamp 37 to ground.

Upon observing the illumination of the white line lamp 37, the switchboard operator plugs in the line jack 14. This separates the line jack ring and tip springs 13 and 12 and at the same time moves the movable contact 35 out of engagement with the fixed contact 34 so as to break the circuit through the white line lamp 37. At the same time the plugging into the line jack places the operator's set (not shown) in circuit with the tip and ring spring contacts 13 and 21 of the line jack, and as the tip spring contact 13 is directly in circuit with the tip side 5 of the circuit through wire 12, armature 10 and tip side 5 and as the ring spring contact 21 is directly in circuit with the ring side 6 of the circuit through wire 20, armature 19 and ring side 6, the operator's set is placed in circuit by plugging in the line jack 14 and a telephone circuit is established between the switchboard operator and the box or substation.

To illuminate the white line lamp 37 when the officer at the substation hangs up his receiver and thereby provide a supervisory signal on the substation circuit when used as a conventional telephone circuit in making substation to substation calls through the switchboard, the armature 31 of the line relay 16 in the deenergized condition of the relay, contacts with a wire 101, this wire being connected with a supervisory spring contact 102 in the line jack. When the line jack is plugged in, the movable spring contact 35 is held in engagement with the supervisory contact 102, but as long as the telephone circuit is in use, the armature 31 of the relay 16 is pulled up so as to render this circuit inoperative. When the parties hang up, however, the relay 16 is deenergized as described and the armature 31 contacts with the wire 101 thereby closing a circuit through battery B, wires 29 and 32, armature 31, wire 101, supervisory contact 102, movable contact 35,

wire 36, white line lamp 37 to ground. The switchboard operator then knows that the parties have hung up and removes the plug from the line jacks of both circuits.

When the switchboard operator desires to call the officer on duty to one of his boxes, he signals the officer who responds to the call in the manner described under the caption "Operation of the signal circuit."

Patrol wagon call

When the officer at the box wishes to make a call for the patrol wagon, he pulls down on the hook of a wagon call switch 38 which effects a wagon call indication at the switchboard and the box, this signalling indication being maintained until the switchboard operator releases the circuit by moving the signal key 24 up to wagon call release position.

The wagon call switch 38 includes a central contact 39 and two contacts 40 and 41, the central contact 39 normally engaging the contact 41 and being movable out of engagement with this contact 41 and into engagement with the contact 40 upon pulling the hook to make a wagon call signal. The central contact 39 is directly connected with the ring side 6 of the line circuit and the contact 40 is connected by a wire 43 with a holding relay 44, the other terminal of which is connected to a grounded wire 45. One armature 46 of the holding relay 44 is connected by a wire 47 with the ring side 6 of the circuit and upon being pulled up engages with a wire 48 connected with the wire 43.

The other armature 49 of the holding relay 44 is connected by a wire 50 with a wagon call buzzer 51, the other terminal of this buzzer being connected by a wire 52 with the contact 41 of the wagon call switch. Upon being pulled up, the armature 49 contacts with a wire 53 which is connected with the tip side 5 of the line.

When the officer pulls the wagon call switch 38 to put in a wagon call, the contacts 39 and 40 are closed and a circuit is established through the battery B, wires 29 and 28, line relay 27, wire 26, closed wagon call contacts 25 and 23 of the signal key 24, wires 22 and 20, armature 19, ring side 6 of the line, central contact 39 and contact 40 of the wagon call switch 38, wire 43, holding relay 44, and wire 45 to ground. The energization of the holding relay 44 pulls up its armature 46 and thereby establishes a holding circuit from the ring side 6 of the line, wire 47, armature 46, wires 48 and 43, holding relay 44 to ground. By this means the circuit is maintained until the ring side circuit is broken at the switchboard.

The energization of the holding relay also pulls up the armature 49 and thus after release of the wagon call switch 38, a circuit is established through the ring side 6 of the line, central contact 39, and contact 41 of the

wagon call switch, wire 52, buzzer 51, wire 50, armature 49, and wire 53 to the tip side 5 of the line.

Before the wagon call switch is released to its normal inoperative position, a circuit has been established over ring side of line to ground which is practically identical with that established by sending an officer's report. When the wagon call switch is released a circuit is then established which is practically identical with that of a telephone call except that the line circuit over tip and ring is held closed through wagon call buzzer 51.

By this means a buzzing circuit is established across the telephone line and the white line lamp 37 at the switchboard will be illuminated as described in connection with the telephone circuit. The operator thereupon plugs into the line jack 14 and receives a buzzing indication in his set which indicates that a wagon call is being made. After noting the wagon call, the switch-board operator moves the signal key 24 up, which movement breaks the contact between the wagon call contacts 23 and 25 and thereby breaks the circuit between the battery B and the ring side 6 of the line. This cutting off of the battery B releases the holding relay 44 and all parts of the wagon call and telephone circuits are restored to normal. By this circuit, the wagon call buzzing indication is maintained both at the box and at the switchboard until the switchboard operator positively releases the circuit. The officer at the box therefore knows that his wagon call has been received.

Officer's report circuit

To insure that the officer is attending to his duties, the officer is required to report at intervals, a printed record of such report being made at the central station preferably by means of a recorder such as described in my copending application, Serial No. 287,617, filed June 22, 1928, for a recording apparatus.

This record is made by the officer at the box closing an officer's report switch 54 one terminal of which is connected with the wire 45 and the other terminal of which is connected 50 by a wire 55 with the wire 50.

At the switchboard, the other armature 56 of the line relay 16 is connected by a wire 57 with the battery wire 32 and when the line relay 16 is deenergized, this armature 56 contacts with a wire 58 connected with one of the armatures 59 of the line relay 27. When this armature 59 pulls up, it contacts with a wire 60 which connects by means of a wire 61 with a holding relay 62. The other terminal of the holding relay 62 is connected by a wire 63 with the recording apparatus (not shown). The armature 64 of this holding line relay 62 is connected by a wire 65 with 60 the battery wire 28 and is pulled up into con-

tact with the wire 60 when the holding line relay 62 is energized.

When the officer at the box closes the officer's report switch 54, a circuit is established through battery B, wires 30, 29 and 28, line relay 27, wire 26, wagon call release contacts 25 and 23 of the signal key 24, wires 22 and 20, armature 19, ring side 6 of line, central contact 39 and contact 41 of wagon call switch 38, wire 52, wagon call buzzer 51, wires 50 and 55, officer's report switch 54, and wire 45 to ground.

When the line relay 27 is energized, it pulls up the armature 59 and thereby establishes a circuit through battery B, wires 30, 29, 32 and 57, armature 56, wire 58, armature 59, wires 60 and 61, holding line relay 62 and wire 63 to recording apparatus.

As the armature 64 of the holding relay 62 is pulled up, it closes a circuit through the battery B wires 30, 29, 28 and 65, armature 64, wires 60 and 61, holding line relay 62 and wire 63 to the recording apparatus. In this manner the recording circuit is held until the recorder makes a record of the time and the box recording and breaks the recording circuit and releases the holding line relay 62 as described in my said copending application for recording apparatus, Serial No. 287,617, filed June 22, 1928. By this means the officer at the box merely has to momentarily close the officer's report switch and the circuit is automatically maintained until a proper printed record is made.

Each time a call is put in for a patrol wagon through the operation of the wagon call switch 38, the recording apparatus associated with the wire 63 at the switchboard is operated to make a printed record of a report from the box called from and the time thereof for the purpose of having a permanent record of such wagon calls together with the regular reports. The circuit through which this report is made is as follows:

Upon pulling the hook on the wagon call switch 38, the central contact 39 thereof is moved into engagement with the contact 40 thereof, and a circuit is established through battery B, wires 29 and 28, line relay 27, wire 26, closed wagon call contacts 25 and 23 of the signal key 24, wires 22 and 20, armature 19, ring side 6 of the line, central contact 39 and contact 40 of the wagon call switch 38, wire 43, holding relay 44, and wire 45 to ground, as described in connection with the wagon call circuit. The energization of the line relay 27, as previously described, pulls up its armature 59 and thereby establishes a circuit through battery B, wires 30, 29, 32 and 57, armature 56, wire 58, armature 59, wires 60 and 61, holding relay 62 and wire 63 to the recording apparatus. The holding relay 62 then holds this circuit until a printed record is made by the recording apparatus and the circuit broken thereby, as described.

The signalling circuit

Adjacent the box an audible signal comprising an electric horn 66 and a visual signal 67 are mounted, these two signals being so arranged as to be visible and audible at a distance from the box, their purpose being to call the officer to the box in order to give him instructions.

These signals are connected by a wire 68 which connects with one terminal of each signal and is also connected by a wire 69 with the tip side 5 of the line. The other terminal of the visual signal 67 is connected by a wire 70 with ground, and the other terminal 10 of the audible signal or horn 66 is connected by a wire 71 with the ring side 6 of the line, a condenser 72 being preferably arranged in this line. By this means, the audible signal circuit is metallic and the visual signal circuit 15 is grounded thereby permitting of their alternate independent operation as will presently appear.

Each of the audible and visual signals is adapted to be intermittently actuated and 20 for this purpose a motor operated flasher 73 is mounted on the switchboard and by the engagement of a salient plate 74 on the rotor, intermittently moves a movable battery contact 75 and a movable transformer contact 76 into engagement, respectively, with a stationary battery contact 77 and a stationary transformer contact 78.

The audible and visual signals of each box are individually controlled by throwing down 25 the signal key 24 which holds its signalling position until manually restored. The throwing down of this key establishes a circuit through the red line lamp 80 on the switchboard, the flasher 73, and the audible 30 or visual signal depending on the position of the master signal switch 81 which controls the signalling effect of all set keys on the switchboard.

The stationary battery flasher contact 77 35 is connected with the battery wire 33 and the corresponding movable contact 75 is connected by a wire 82 with the movable signal contact 83 of the signal key 24. The fixed signal contact 84 is connected by a wire 85 with the red line lamp 80 on the switchboard and the other terminal of this red line lamp is connected by wires 86 and 87 with the other armature 88 of the line relay 27. This armature 88 is connected by a wire 89 with a 40 grounded wire 90. To simultaneously energize the line relay 11, as presently described, one terminal of this relay is connected by a wire 91 with the fixed signal contact 84 while the other terminal of this relay connects with the wire 86.

The signals are actuated from a transformer T, the primary coil 92 of which is connected to alternating current supply wires 45 93 and 94 and the secondary coil 95 of which

is connected by a wire 96 with the fixed flasher contact 78, while the other terminal of this secondary coil 95 is connected with a wire 97, which wire 97 is adapted to contact with the armature 10 of the line relay 11 when this relay is energized. 70

The master signal switch 81 comprises a manually operable contact 98 which is normally held in contact with the grounded wire 90 and is manually movable into contact with a wire 99. The wire 99 is engaged by the armature 19 of the line relay 11 when the line relay 11 is energized. The movable contact 98 of the master signal switch is connected by a wire 100 with the movable transformer 75 flasher contact 76 of the flasher 73. 80

Operation of the signal circuit

The switchboard operator throws the signal key 24 down which closes the signal contacts 83 and 84. This downward position is automatically held until the signal key is manually reset.

This movement of the signal key establishes a circuit through battery B, wire 30, 90 and stationary and movable battery contacts 77 and 75 of the flasher 73, wire 82, movable and fixed signal contacts 83 and 84 of the signal key 24, wire 85, red line lamp 80, wires 86 and 87, armature 88 and wires 95 89 and 90 to ground. The red line lamp 80 on the switchboard is thereby flashed on and off to indicate that the corresponding signal key is set to give a visual or audible signal at the corresponding box or substation. 100

At the same time line relay No. 11 is energized to pull up its armatures and place the transformer T in circuit with the flasher and the visual or audible signal. This relay 11 is energized through the following circuit: battery B, wire 30, stationary and movable battery contacts 77 and 75 of the flasher 73, wire 82, movable and fixed signal contacts 83 and 84 of the signal key 24, wire 91, line relay 11, wires 86 and 87, armature 88, and wires 89 and 90 to ground. The line relay 11 is therefore energized and pulls its armatures 105 19 and 10 into contact, respectively with the wires 99 and 97.

Assuming that the master signal switch 81 is in its normal position shown, in which its movable contact 98 is in engagement with the grounded wire 90, the visual signal will be flashed on and off through the following circuit:

Ground G, wire 90, master signal switch contact 98, wire 100, movable and fixed transformer flasher contacts 76 and 78, wire 96, secondary coil 95 of the transformer, wire 97, armature 10 of energized relay 11, tip side 5 120 of line, wires 69 and 68, visual signal light at box and wire 70 to ground. Through this grounded circuit an intermittent operation of the visual signal light 67 at the box will be maintained, the circuit being made and 125 130

broken through the flasher 73 which continuously makes and breaks this circuit.

If an audible signal indication through the horn 66 at the box is desired, the master signal switch 81 is automatically moved so that its contact 98 engages the wire 99 and establishes a metallic circuit through the transformer, flasher and audible signal as follows:

- 10 Secondary coil 95 of the transformer, wire 97, armature 10 of line relay 11, tip side 5 of line, wires 69 and 68, audible signal horn 66, wire 71 and condenser 72, ring side 6 of line, armature 19 of energized line relay 11, wire 99, master signal switch contact 98, wire 100, movable and stationary condenser flasher contacts 76 and 78, and wire 96 to the other terminal of the secondary coil 95. By this means as long as the master signal switch 20 contact 98 is held manually in engagement with the wire 99, a metallic circuit through the audible signal 66 is maintained and the same alternately actuated by the making and breaking of the circuit by the flasher. After 25 several blasts, the switchboard operator releases the master signal switch 81 and the grounded circuit through the visual signal 67 is maintained until the officer responds to the signal.
- 30 The transformer T, flasher 73 and master signal switch 81 are common to all of the line circuits and hence the operation of the master signal switch to give either an audible or a visual signal affects all of the signal circuits.
- 35 the signal keys 24 of which are set to signalling position. By this means in calling a number of boxes, the signal keys of these boxes are set to signalling position, and after being set the master signal switch is held 40 down for a short interval to give a few audible blasts on the horn 66, and then the master signal switch is released thereby continuing the visual signal until the officer or officers being called respond. In this manner the 45 time to change the signalling circuits from visual signalling circuits to audible signalling circuits and vice versa is materially reduced as compared with circuits in which this change is effected through the individual 50 signal keys.

When the substation circuit is in normal or inoperative condition, the armatures 19 and 10 of the line relay 11 provide a complete telephone path from the substation 55 through relays 16 and 27, line jack 14 and battery B, as previously described. During the intervals, however, when the substation visual or audible signals are operated from the switchboard, the relay 11 pulls up its 60 armatures 19 and 10 and thereby disconnects all of the central station telephone equipment associated with the substation lines and transfers the substation circuit at this point to the source of energy for operating the 65 substation signals. Therefore anyone an-

swering the telephone at the substation at this instant, would not be able to signal the central station upon removing the receiver from the hook switch 8, since during this signalling interval the signal energy would 70 pass through the substation telephone receiver 7 and transmitter 9. The telephone receiver 7 does not include a permanent magnet but is of the electro-magnetic type and therefore the alternating current used for 75 signal operation causes no damage to the receiver when it is lifted during a signalling condition of the circuit.

The signal circuit is intermittently energized through the flasher 73, and as soon as the flasher contacts 77 and 75 break, the relay 11 is released and the armatures 19 and 10 thereof move into engagement with the wires 20 and 12 and thereby restores the telephone circuit or couples the switchboard telephone equipment with the substation circuit and the fact that the officer has lifted the receiver is noted by the illumination of the white line lamp 37 at the switchboard as described under the caption "Telephone circuit" and the 90 switchboard operator then answers the substation call. During the time when the telephone circuit is in operation, no signal energy can pass over the substation circuit for the reason that the line relay 11 can operate 95 only when one side of its winding is connected to ground through wires 86 and 87, armature 88, and wires 89 and 90 to ground. When a telephone call circuit is established 100 by lifting the receiver from the hook at the substation, the relay 27 becomes operative thereby breaking the connection between wire 87 and armature 88 thereby disconnecting the ground from relay 11 at this point. This prevents further operation of relay 11. 105

The condenser 72 must be of relatively large capacity so that the audible signal 66 can be operated with current necessary for its proper operation. This condenser is essential in the substation circuit to prevent battery current flowing over the substation circuit from flowing through the audible signal 66 under normal conditions. This condenser carries a relatively high charge when the signal energy is disconnected at the contacts 76 and 78 of the flasher 73. Therefore when the relay 11 restores the substation circuit to its normal connection with the switchboard telephone equipment after each signal interval, a path is provided through the relays 60 and 27 over which the condenser 72 would discharge in the absence of provision to prevent it. This discharge would cause a disagreeable reaction in the substation circuit, that is, a momentary flashing of the white line lamp 37 through the momentary closing of the armature 31 of the line relay 16 and might also cause the recorder to operate through the momentary operation of the relay 27. 115 120 125 130

To prevent either of these from occurring, a means is provided for discharging the condensers 72 of all operative substation circuits through a grounded contact 79 mounted in the rotor of the flasher 73. To clearly understand how this occurs, I give the following description of the flasher construction:

The mechanical design of the flasher 73 is such that the battery contacts 75 and 77 close before the transformer contacts 76 and 78 are closed. This permits all of the signal control relays 11 that may be in use to come into operation before the transformer flasher contacts 76 and 78 are closed. In reverse order, the transformer flasher contacts 76 and 78 break the transformer circuit before the battery flasher contacts 75 and 77 break the battery circuit. There is therefore a slight time interval after the signal energy has been disconnected from the substation circuits before the substation signal relays 11 are disconnected and restored to normal telephone relation. During this interval, the transformer flasher contact 76 which is common to the ring side of all substation circuits which are in a signal operative position, drops from the salient plate 74 of the flasher 73 and engages the grounded contact 79 on the rotor of the flasher 73. This provides a discharge circuit for the condenser 72 before the relay 11 has an opportunity to restore the substation circuit to its normal inoperative position. This discharge circuit is as follows:

Flasher ground, contact 79, flasher contact 76, wire 100, master signal switch spring 98, wire 99, armature 19 of line relay 11, ring side 6 of line, condenser 72, wire 71, audible signal 66, wire 68, visual signal 67, and wire 70 to ground. As will be noted in this description, this circuit will be completed only when the master signal switch 81 is in a position for operating the audible signals at the substations. During such periods when the master signal switch 81 is in normal position shown in Fig. 1 and the visual signals 67 are operated, there is no necessity of providing a discharge circuit.

Another important reason why the flasher 73 is so designed and constructed to cause the battery flasher contacts 75 and 77 to close before the transformer flasher contacts 76 and 78 close and also the transformer flasher contacts to open before the battery flasher contacts open is to establish closed circuits through the contacts on line relay 11 and over the substation circuit and also to disconnect the signal energy from the substation circuits over the contacts of relay 11 before these contacts break to prevent any arcing from occurring on these contacts on substation circuits.

As a whole this signal system performs all necessary functions of a police signal system, it is simple to operate and not liable to lead to erroneous signals, and provides simple circuit arrangements which will not easily get out of order and can be readily repaired.

I claim as my invention:

1. In combination with a telephone system, a police signal system, comprising a central station, a plurality of substations and circuits connecting said central station with said substations, a power source associated with said substation circuits, a visual and an audible signal device at each of said substations, and a master switch at said central station and associated with said power source and all of said substation circuits, said master signal switch in one position being adapted to supply energy from said power source for the operation of any group of said visual signal devices and in another position being adapted to supply energy for the operation of the corresponding audible signal devices.

2. In combination with a telephone system, a police signal system, comprising a central station, a plurality of substations and circuits connecting said central station with said substations, a power source associated with said substation circuits, a visual and an audible signal device at each of said substations, each of one type of said signal devices being connected across the respective circuit and each of the other type of said signal devices being grounded, and a master signal switch at said central station and common to all of said substation circuits and said power source, said master signal switch in one position being grounded and being adapted to supply energy from said power source to any of said grounded signal devices as a group and said master signal switch in another position being connected across said substation circuits and said power source and being adapted to supply energy to the corresponding other type of signal devices as a group.

3. In combination with a telephone system, a police signal system, comprising a central station, a plurality of substations and circuits connecting said central station with said substations, a power source associated with said substation circuits, a grounded visual signal device at each of said substations, a signal switch associated with each of said substation circuits and operating, when closed, to energize one of said signals of its respective circuit, an audible signal device at each of said substations and connected across the substation circuit, a signal switch associated with each of said substation circuits and operating, when closed, to energize one of said signals of its respective circuit, and a master signal switch at said central station and common to all of said substation circuits and said power source, said master signal switch in one position being grounded and being adapted to supply energy from said power source to any of said grounded visual signal devices as a group and said master signal switch in another position being connected across said

substation circuits and being adapted to supply energy from said power source to the corresponding audible signal devices as a group.

- 5 4. In combination with a telephone system, a police signal system, comprising a central station, a plurality of substations and substation circuits connecting said central station with said substations, a visual signal device at each of said substations and having one terminal connected with one line of the substation circuit and its other terminal being grounded, a signal switch associated with each of said substation circuits and operating, 10 when closed, to energize one of said signals of its respective circuit, an audible signal device at each of said substations and being connected across the substation circuit, a common source of energy in said one line of each 15 substation circuit, a signal switch associated with each of said substation circuits and operating, when closed, to energize one of said signals of its respective circuit, and a master signal switch at said central station and common to all of said substation circuits from said power source, said master signal switch in its normal position grounding said one line of each substation circuits and thereby energizing all of said visual signal devices 20 of the circuits set up by said signal switches as a group and said master signal switch in another position being connected across each of said substation circuits and thereby energizing the corresponding audible signal devices 25 as a group.

5. In combination with a telephone system, a police signal system, comprising a central station, a plurality of substations and circuits connecting said central station with said substations, a power source associated with said substation circuits, a visual and an audible signal device at each of said substations, means at said central station for selectively setting up individually any number of substation signal circuits and supplying energy to operate the respective visual signal devices and master means for changing said set visual signal circuits to audible signal circuits as a group.

50 6. In combination with a telephone system, a police signal system, comprising a central station, a plurality of substations, and substation circuits connecting said central station with said substations, a power source associated with said substation circuits, a visual and an audible signal device at each of said substations, means at the central station for individually setting up any number of substation signal circuits and supplying energy to operate said visual signal devices, and a master switch associated with said substation circuits and adapted to supply energy to the audible signal devices of said set signal circuits as a group.

65 7. In combination with a telephone sys-

tem, a police signal system, a central station, a plurality of substations, and circuits connecting said central station with said substations, a power source associated with said substation circuits, means at said central station for setting up any number of substation signal circuits, a grounded visual signal device at each substation and connected with the corresponding substation circuit, an audible signal device at each substation and connected across the corresponding substation circuit, an individual switch for setting up each circuit and energizing one of the signals thereof and a master signal switch at said central station and common to all of said substation circuits, said master signal switch in one position being grounded and being adapted to supply energy to all the grounded visual signal devices on the set signal circuits and in another position being connected across said substation circuits and being adapted to supply energy to the audible signals on the set signal circuits as a group.

8. In combination with a telephone system, a police signal system, a central station, a plurality of substations and substation circuits connecting said central station with each of said substations, means at said central station for setting up and energizing any number of substation signal circuits, a visual signal device at each substation and having one terminal connected with one line of the substation circuit and its other terminal being grounded, an audible signal device at each substation and being connected across the substation circuit, a common source of energy in said one line of each substation circuit, and a master signal switch at said central station and common to all of said substation circuits, said master signal switch in one position grounding said one line of each set substation circuit and thereby energizing the corresponding visual signal devices as a group and said master signal switch in another position being connected across each of said substation circuits and energizing the audible signal devices on the set substation circuits as a group.

9. In combination with a telephone system, a police signal system, a central station, a plurality of substations and substation circuits connecting said central station with each of said substations, each of said circuits including a primary switchboard circuit having a relay and a switch for setting up said primary circuit and energizing said relay and a secondary circuit rendered operative by the energization of said relay and each secondary circuit including a grounded visual substation signal device connected with one side of said secondary circuit, an audible substation signal device connected across said secondary circuit and a master signal switch and source of energy common to all of said secondary circuits, said master signal

switch being adapted in one position to be connected across said secondary circuits and energize the audible substation signal devices of all set circuits and in another position to ground one side of each of said secondary circuits and energize the visual substation signal devices of all set circuits.

10. In combination with a telephone system, a police signal system, a central station, a plurality of substations and substation circuits connecting said central station with each of said substations, each of said circuits including a primary switchboard circuit including a relay having two armatures and a switch for setting up said primary circuit and energizing said relay, and a secondary circuit having a tip side in circuit with one of said armatures and a ring side in circuit with the other armature, a grounded visual substation signal device connected with said tip side, an audible substation signal device connected across said ring and tip sides and a master signal switch and source of energy common to all 25 of said secondary circuits, said master signal switch in one position being adapted to establish a circuit across said ring and tip sides on all set substation circuits and thereby energize the audible substation signal devices on all set circuits and in another position to establish a circuit through said grounded visual signals on all set circuits.

11. In combination with a telephone system, a police signal system, a central station, a plurality of substations and circuits connecting said central station with each of said substations, each of said circuits including a primary switchboard circuit comprising a relay having two armatures, a battery and a switch for setting up the primary circuit and energizing said relay and a secondary circuit having a tip side in circuit with one of said armatures and a ring side in circuit with the other armature, a grounded visual substation signal device connected with said tip side, an audible substation signal device connected across said ring and tip sides, a source of electrical energy in said tip side, and a master signal switch common to all 45 of said secondary circuits and adapted in one position to establish a circuit across said ring and tip sides on all set circuits and energize the audible substation signal devices thereof and in another position to ground said tip sides on all set circuits and establish a circuit through all visual signal devices thereof, said master signal switch being normally held in the position in which it grounds the tip sides and energizes the visual signal devices.

60 In testimony whereof I affix my signature.
GUSTAV F. C. BAUER.
